ARRANGEMENT FOR REGULATING THE VOLTAGE OF A GALVANIC BATH

Josef Kälin, Rheinfelden, Switzerland

Application January 7, 1948, Serial No. 937

3 Claims. (Cl. 323—66)

1

The present invention relates to an arrangement for regulating the voltage of a galvanic bath. It has for its object to keep the potential between anode and cathode constant within a range which produces the most favourable effect as regards the galvanising action. It is known that when the potential is too low, the output is correspondingly smaller, but when the potential or voltage is too high, the galvanic coating is of poor quality, since it forms then a foamy texture and thus appears to be dark to black in color and is also not durable.

The arrangement according to the invention for regulating the potential or voltage in galvanic baths is characterised by a voltage relay connected between anode and cathode and an auxiliary current circuit for the actuation of at least one regulating resistance, said auxiliary current circuit being controlled from the voltage relay.

One construction of the arrangement according to the invention shows by example two regulating resistances as indicated diagrammatically in the accompanying drawing.

1 is a galvanic bath with the two pole leads 2 and 3 connected to a current source 4. The latter may, for example, consist of a direct current dynamo, an accumulator battery or a rectifier. It is important, however, to regulate the terminal voltage delivered by this current source, as shown in the drawing 4. The current source is a regulatable shunt generator with the connecting terminals 5, but, it could also be an accumulator battery (not shown) controlled by means of battery switches. 6 is an auxiliary current source, the energy of which serves for the actuation of the regulating or compensating resistances. The leads from this auxiliary current source 6 are indicated by 7 and 8. 9 is a switch that is controlled by a solenoid 10 which is actuated from the main leads 2 and 3.

A voltage relay 11, which is connected to the two main leads 2 and 3 by means of the leads 12 and 13, serves the purpose of giving the impulse for the regulation of the voltage in the bath 1. The relay 11 includes a contact arm 14 which, depending upon an undervoltage or an overvoltage in the bath 1, causes the closing of circuits by contacting the respective contacts 15, 16, which circuits include the solenoids 17 and 18. These current circuits are branches from the auxiliary current leads 7 and 8. Depending upon whether contact 15 or contact 16 is connected with the contact arm 14, a lead 19 or 20 will be placed under current, since the latter closes the respective switches 21 and 22 by action of solenoids 17 and

2

18, respectively. Lead 19 leads to the pivot point of a first tilting switch 23 and the lead 20 to the pivot point of a second tilting switch 24.

Connected to the main lead 3 is a compensating resistance 25, the switch arm 26 of which serves at the same time as actuating member for the tilting arms 23, 24. In their normal position, the tilting switches 23, 24 are forced under the influence of springs (not shown in the drawing) 10 towards contacts 27 and 28 respectively. From these contacts 27 and 28 the leads 29 and 30 pass to solenoids 31 and 32, respectively, the opposite poles of which are both connected to the auxiliary current lead 7. These solenoids 31 and 32 serve for the mechanical actuation of switches 33, 34, 35 and 36 controlling the armature current of a motor 37 which, through its shaft 38 and a gear drive (not shown, but consisting, for example, of a worm transmission), actuates the switch arm 26. The armature windings are indicated by 39 and the field windings connected with the auxiliary current leads 7 and 8 by means of the leads 40. Instead of the field windings 40 always being kept under current when the motor 37 is not operative, thereby consuming current unnecessarily and heating up the exciter coils, it is also possible to incorporate interrupters in these leads 40, said interrupters automatically becoming operative as the motor stops.

For the mechanical actuation of the switches 33, 34, 35 and 36, these are coupled with the cores of the solenoids 31 and 32 by insulating elements 41 and 42, the solenoid 31 actuating the switches 33 and 34 and the solenoid 32 the switches 35 and 36.

If the switch arm 26, according to the drawing, is moved towards the left (see drawing) until it swings the tilting arm 23, then the latter comes into contact with a contact 43 to which is connected the lead 44. Conversely, if the switch arm 26 is moved into the opposite end position, then it is the tilting lever 24 that is swung and thus comes up against a contact 45 from which the lead 46 extends.

The compensating or regulating resistance, with the associated motor for actuating same and the switches actuated by solenoids are represented as the first regulator aggregate R1. A similarly constructed second regulator aggregate RII is provided in order to regulate the terminal voltage of the bath current source. The latter aggregate receives the impulse from the above-described first aggregate through the leads 44 and 46.

This second regulator aggregate RII again con-

sists of a compensating resistance 47 with a switch arm 48, the former being connected by the lead 49 to the pole lead 3 and the switch arm 48 being connected by the lead 50 to the connecting terminals 5. The actuation of the switch arm 48 is likewise effected by a motor 51 through a shaft 52 by means of a gear drive (not shown). The switch arm 48 also serves, in the end positions, to operate two tilting switches 53 and 54, which, in their normal position, bear under spring action against contacts 55 and 56 which are connected to the leads 44 and 46, respectively, coming from the first regulator aggregate RI. Leads 51 and 58 extend from the tilting switches 53 and 54 to solenoids 59 and 60 which are connected at their other sides to the auxiliary current lead 7. These solenoids 59 and 60 serve for the mechanical actuation of switches 61, 62, 63 and 64, which are provided for the control of the armature current of the motor 51. In this arrangement, the solenoid 59 is coupled with the switches 61 and 62 by way of an insulating connection 65 and the solenoid 60 with the switches 63 and 64 in such a manner that the switches 61 and 62 or 63 and 64, respectively, are switched on or off, respectively, by the response of the solenoids 59 or 60. The armature leads to the motor 51 are indicated at 67 and the field leads at 68, the same remarks applying to the latter as regards interruption as for the field leads 40.

69 are frames for receiving the compensating resistances and the rectangles 70, 70¹, 70² and 70³ in dotted lines represent instrument tables.

The arrangement illustrated operates in the following manner:

First of all, the bath current is switched on and thus the anodes and cathodes are supplied with current. The auxiliary current circuit is also closed by this action by means of the switch 9. When the bath is not charged, the voltage therein is approximately equal to the idle running voltage delivered by the current source 4. By charging the bath with articles to be galvanised, the voltage between anode and cathode drops in proportion to the surface area of the articles. In order to prevent an unnecessary oscillating operation of the arrangement with the bath uncharged, inasmuch as the bath voltage may be somewhat too high despite the resistances even when being fully switched on, one plate of the said bath serving as anode, or a sufficiently large iron or copper sheet, suspended as a so-called current screen on the cathode side, may be used for lowering the voltage. The voltage in the bath drops upon charging, whereby the voltage relay 11 is set in motion until its contact arm 14 comes to rest against one or the other contact 15 or 16, according to whether there is an undervoltage or overvoltage with respect to a mean operating voltage. Assuming that there is contact at 15 as a result of an undervoltage, then a circuit is closed between the auxiliary leads 7 and 8 by way of the solenoid 17. By closing the switch 21, a current circuit is closed from the lead 8, through this switch 21, the lead 19, the tilting switch 23 and, from this, by way of the contact 27, the lead 29 and the solenoid 31, to the lead 7. In this way, the solenoid 31 actuates the switches 33 and 34 in the closing direction. The motor 37 receives armature current and actuates the switch arm 26 in the direction for switching or cutting out resistances 25, whereby the bath voltage is raised. If the resistance is switched out as far as the end position, without the bath voltage being raised sufficiently, then the tilting lever

23 is moved by the switch arm 26 in such a manner that the afore-mentioned circuit is opened at 27 and thus the motor 37 comes to a stop. On the contrary, if the tilting lever 23 comes up against the contact 43 and conducts the current coming from the lead 8 through the lead 44 to the contact 55 in the second regulator aggregate RII and from thence, by way of the tilting switch 53 and the lead 57, to the solenoid 59, which is connected on its other side with the lead 7, and thus its circuit is closed. Consequently, this solenoid 59 responds and closes the switches 61 and 62, thereby supplying armature current to the motor 51. This raises the field voltage of the shunt generator 4 by such an amount that the potential between the pole leads 2 and 3 is increased. In the end position of the switch arm 48, the tilting lever 53 is interrupted and consequently the supply of current from the auxiliary supply 7, 8 to the armature of the motor 51 is interrupted.

The dimensions of the resistances 25 and 47 are such that in their limiting positions, even with the bath fully charged, there is a sufficient voltage in said bath.

If an overvoltage exists in the bath, due, for example, to the articles being removed therefrom, the switch arm 14 is moved against the contact 16. Upon coming into contact therewith, the switch 22 is closed by the solenoid 18 and the current flows from the lead 8 through the lead 28 towards the tilting lever 24, and, through the lead 30, actuates the solenoid 32, which closes the switches 35 and 36, whereby the motor 37 receives armature current causing the motor 37 to turn in opposite direction so that it places resistance 25 into the main circuit. In the end position of the arm 26, the lever 24 is disconnected from contact 28 and passed over to the contact 45, whereby the current flows through the lead 46 to the contact 56, through the tilting switch 54 and the lead 58 to the solenoid 60. This closes the switches 63 and 64 and consequently supplies armature current to the motor 51 in such a manner that the resistance 47 is placed in circuit and thus the potential between the pole leads 2 and 3 is lowered.

It has been shown in practice that the switches 21 and 22 actuated by the solenoids 17 and 18 are not absolutely necessary, but the contact members 15 or 16, respectively, could be placed directly on the leads 19 and 20, respectively, so that the current of the auxiliary circuit from the lead 7 is led directly to the tilting switches 23 or 24, respectively, by way of the switch arm 14 on the relay 11.

The limits of the voltage to be maintained are adjusted in practice by displacing the contact members 15 and 16 towards or away from one another, since the voltage range is reduced by bringing these contact members closer together and increased by moving them apart.

Moreover, with the arrangement described, several baths may also be controlled simultaneously as regards voltage, it being pre-supposed, of course, that all the baths have the same voltage requirements.

Furthermore, the installation may also be so provided that several baths are served from a single source of bath current, even if the individual baths require different voltages. In this case, each bath is, for example, controlled from a separate first regulator device, all of which are then connected with the common regulator device for the main current supply 2, 3.

Depending upon the form of the bath current source, the second regulator aggregate can be dispensed with and replaced by a press button control means.

Having now particularly described and ascertained the nature of my said invention and in what manner the same is to be performed, I declare that what I claim is:

1. In an arrangement for regulating the voltage of a galvanic bath, a power source, a first circuit connecting the power source with said galvanic bath, a second circuit, a second energy source and at least a first regulating aggregate in said second circuit, said aggregate comprising a first variable resistance and an electric motor, the armature coil of said motor being in said second circuit, the first variable resistance of said first aggregate being in said first circuit and a second variable resistance of a second aggregate controlling the field voltage of a shunt generator forming said power source, said second variable resistance being put into operation upon disconnecting the control means of said first variable resistance, each electric motor controlling the corresponding variable resistance, switch means responsive to the voltage in the first circuit to reverse said armature coil of each motor in the second circuit, and means controlled by the respective variable resistances to open the circuit to the corresponding armature coil of each motor.

2. The arrangement as set forth in claim 1, in which the variable resistance of the first aggregate controls switch means for disconnecting at a predetermined point of said resistance the first aggregate and for connecting the second aggregate.

3. In an arrangement for regulating the volt-

age of a galvanic bath, a power source, a first circuit connecting the power source with said galvanic bath, a first variable resistance in the first circuit, a voltage relay between anode and cathode of the bath controlling the first resistance, a second variable resistance controlling the terminal voltage of said power source and being controlled by the first resistance, a second circuit including a second energy source and armature coils for motors controlling the first and second resistance, respectively, switch means controlled by said voltage relay for reversing the armature coils in the second circuit and means controlled by the first resistance for disconnecting at a predetermined point thereof the armature coils of the motor controlling the first resistance and connecting the armature coils of the motor controlling the second resistance.
